UNITED STATES PATENT OFFICE

144,791

DESIGN FOR A CLOTHES HAMPER

Jack J. Kohen, South Bend, Ind.

Application March 9, 1945, Serial No. 118,373

Term of patent 14 years

(Cl. D58—4)

To all whom it may concern:

Be it known that I, Jack J. Kohen, a citizen of the United States, residing at South Bend, in the county of St. Joseph, State of Indiana, have invented a new, original, and ornamental Design for a Clothes Hamper, of which the following is a specification, reference being had to the accompanying drawing, forming a part thereof.

Fig. 1 is a front perspective view of the clothes hamper, showing my new design.

Fig. 2 is a front perspective view of the clothes hamper with its lids raised.

The left-hand side and the rear of the article have the same appearance and are duplicates of the side and front, respectively, as shown in the drawing.

I claim:

The ornamental design for a clothes hamper, as shown and described.

JACK J. KOHEN.
